UNITED STATES PATENT OFFICE.

BRUNO FORBRIGER, OF SCHÖNEFELD, NEAR LEIPSIC, SAXONY, GERMANY.

SWING-TENT.

SPECIFICATION forming part of Letters Patent No. 425,540, dated April 15, 1890.

Application filed October 9, 1889. Serial No. 326,403. (No model.)

To all whom it may concern:

Be it known that I, BRUNO FORBRIGER, of Schönefeld, near Leipsic, in the Kingdom of Saxony, Germany, have invented a new and useful Swing-Tent, of which the following is a specification.

This invention is illustrated in Figures 1 to 15 of the drawings, in which—

Fig. 1 is a side view of the rocking tent, the tent-cover being cut away. Fig. 2 is an end view of the same; Fig. 3, a side view of same in a rocking position; Fig. 4, a side view of the frame folded singly; Fig. 5, a sectional end elevation of same; Fig. 6, a side view of the same doubly folded; Fig. 7, a sectional end view of Fig. 6; Fig. 8, a front view of turning-spindle on an enlarged scale; Fig. 9, a side view of the rests or stops *f f* and adjacent parts; Fig. 10, a sectional side view of one of the turning-spindles; Fig. 11, elevation of coupling for the middle upper yoke; Fig. 12, a transverse section, and Fig. 13 a plan, of the same. Fig. 14 represents the fastening for tent-cover with middle yoke in sectional end view, and Fig. 15 the same in plan.

The above-illustrated invention is for a folding tent-frame which can be used in place of life-saving baskets and many other purposes. This tent-frame, owing to its folding and rocking nature, is constructed in a peculiar manner.

It consists, principally, of a series of open bent sections or yokes preferably arched which attain their purpose in divers manners, and the particular construction is illustrated in the drawings and the following description.

The tent-frame is shown in position for use in Figs. 1, 2, and 3, and in a folded position in Figs. 4 to 7, while Figs. 8 to 12 show various details of construction.

40 The arched sections or yokes A and B of the tent-frame serve to support the whole structure. They rest upon the ground and are braced from each other by means of the folding brace K. The arched sections or yokes 45 A and B are also rockers and serve for rocking the tent.

The arched sections or yokes E F serve for holding the tent-cover, and the adjacent arched sections or yokes C D, forming the up-

per part or roof of the tent, (see Figs. 11 to 15,) 50 are held together by means of a peculiar coupling consisting of a clasp G or a spring.

All of the arched sections or yokes are pivoted and turn upon the spindles *a a* at their ends, and the ends of these spindles are so 55 constructed (for example, with loops or eyes, as shown) as to allow a hammock to be swung upon them. (See Fig. 1.) All the sections or yokes are jointed in the middle by joint *b*, so that they can be folded so as to resemble 60 a quadrant. (See Fig. 6.) The spindles *a a* are provided with the rests off (see Figs. 8 to 10) for the purpose of supporting the sections or yokes E F, and by means of which, when the tent is erected, the sections or yokes E F are 65 in a state of tension with respect to C D. (See Fig. 2.)

The folding of the tent-frame is as follows: The upper sections or yokes C D are separated and the jointed braces K are folded. The 70 cover is taken off and rolled up. The frames A B C D E F lie close together, one above the other, as shown in Fig. 4, forming a semicircle, and by means of the joint C they may be folded in the form shown in Fig. 6. In this 75 manner the tent can be folded in a very small compass and is readily portable, and has the advantage that the body of the person resting can receive not alone the rocking motion from the hammock, but from the whole tent, 80 which will generally be done mechanically by the action of the wind, especially when the outer surface of the tent is properly turned to the wind. This arrangement of tent is superior to the ordinary ones, not alone on account 85 of the superior comfort afforded, but also in the practical nature of the construction.

I claim—

1. A tent-frame composed of a series of yokes, in combination with spindles to which they 90 are pivoted at their ends, all substantially as described.

2. A tent-frame consisting of a series of arched sections jointed substantially in the middle, in combination with and pivoted at 95 their ends on two spindles, whereby the tent-frame may be folded up into quadrant shape, all substantially as described.

3. A tent-frame consisting of a series of open bent sections or yokes, in combination with and connected at their ends to spindles, said spindles being provided with loops for attaching a hammock, all substantially as described.

4. In a tent-frame, the combination of the yokes A, B, C, D, E, and F, pivoted at their ends on the spindles *a a*, provided with stops *ff*, the yokes A and B being connected by the

jointed braces K K, all substantially as described.

In testimony whereof I have signed my name to this specification in the presence of two subscribing witnesses.

BRUNO FORBRIGER.
